UNITED STATES PATENT OFFICE

FREDERICK C. SCHOLLER, OF PHILADELPHIA, PENNSYLVANIA.

STOCKING FORM.

Application filed March 5, 1926. Serial No. 92,436.

My invention relates to forms for stretching stockings or other garments while they are being dried.

The purpose of my invention is to give desirable space for air circulation in a form intended for domestic use.

A further purpose is to provide for stiffness and strength in a form offering ventilation.

10 Further purposes will appear in the specification and in the claims.

I prefer to illustrate my invention by one general type only among various types in which it may appear, selecting one which is 15 practical, effective and inexpensive and which at the same time well illustrates the principles of my invention.

Figure 1 is a side elevation of the form embodying my invention applied to a stocking form.

Figure 2 is a section of Figure 1 taken on line 2—2, to which the sections of a stocking has been added.

Figure 3 is a section corresponding to the 25 section in Figure 2 but omitting the stocking and showing a sheet metal construction.

Fragmentary Figures 4 and 5 show slightly different shapes in section.

In the drawings similar numerals indicate 30 like parts.

The very general washing of stockings and other garments by wearers and subsequent drying them without ironing has emphasized the inadequacy of existing forms 35 for properly holding the garments while they are drying and at the same time giving them shape; and my invention is intended to meet this increasing need.

Because the invention finds its best application as applied to hosiery I shall describe it in this use.

My form may be made of any suitable material or combination of materials which will not stain or tarnish in use in a manner 45 to injure the fabric. Compositions, metals or alloys otherwise unsuitable may be finished with a lacquer or other protective coating for the same purpose.

The form comprises, generally, a flanged border 5 and a stiffening and supporting interior 6 shown in the form of a web. It is shown as of cast, molded or pressed material in the illustration of Figures 1, 2, 4 and 5.

The border 5 presents an edge 7 and laterally spacing flange members, 8, 8', stretching the fabric 9 free from the web as seen

in the section of the stretched stocking shown in Figure 2.

Between the edge 7 and the spacing flanges 8, 8', the contour is hollowed or relieved at 60 10 so as to space the stocking from the form here. The contour at 11 curves toward the center from the flanges 8 and 8' and the webs lie well between the planes defined by the crests of the flanges.

65 The web 6 is apertured as at 12 to allow free passage of air from one side to the other and hence to permit air to pass through the stocking without serious interference from the form. I have shown many small holes 70 but the number, shape and size are of course, not material.

The web 6 is reinforced by oppositely extending longitudinal reinforcing ribs 13 and 14 and transverse ribs 15.

75 The inwardly-turned contour of the flanges 8, 8' at 11 and the thinness of the web protect the stocking from contact with the form between the flanges 8 and 8 on the one side and flanges 8' and 8' on the other facilitating 80 the ventilation noted above and greatly reducing the time of drying.

The border 5 may be apertured to ventilate between the flanges and the adjacent edges or at the flanges, as at 18.

85 The corrugated or ribbed structure would itself space the stocking from the intervening body of the form and in combination with the apertures providing for air passage through the stocking and form would give 90 desirable results—though not as good as I secure—even without the additional lateral spacing given by the flanges.

What for convenience I have called flanges is in effect a rim or border giving lateral 95 spacing and may form the actual rim. Thus, where the creases at the front and back are not desired, what I have named as the edge may be rounded and part of the advantage of

my invention may be secured without the 100 relief of the material at 10, particularly because of the benefit of capillary attraction. By this attraction the moisture in the portion of the stocking which still remains wet flows out into adjoining portions which have 105 dried, resulting in a flow from the more slowly drying portions in contact with the flanges or rim into that portion of the stocking which is stretched across from flange to flange and spaced from the web. I believe at 110

so as to reduce the portions which will thus dry relatively slowly and reduce the distance

which the moisture must travel to drier portions of the stocking by capillary attraction. This relief at 10 can be used where its benefit is desired and omitted, making the contour here straight or convex as in Figures 4 and 5, where the drying is considered sufficiently rapid for the purpose intended.

The illustration in Figure 3 corresponds in contour with Figure 2 but is made of sheet material which extends outwardly from the web to form the flanges 8, 8 and is then turned back on itself at the edges 7 to form the other flanges 8', 8', terminating preferably at some such line as 16. It is hollow at 17 and may be apertured as at 18' to provide air circulation across from flange to flange, corresponding generally with the circulation across the web.

The spacing and stiffening flanges near the edge, the relief from contact between the flanges and the edge and the stiffening ribs in the web along with the apertures well carry out the intended function, giving quick drying with shaping and creasing.

In view of my invention other forms will doubtless occur to those skilled in the art, embodying all or a part of my invention and suiting the whim of the designer or merely avoiding copying mine and I, therefore, intend to include herein all such as come within the reasonable spirit and scope of my invention.

Having thus described my invention, what I claim as new and desire to secure by Letters Patent is:—

1. A stocking form comprising a longitudinally corrugated web, a rim of greater thickness than the thickness given by the corrugations, extending about the web and relatively sharp edges about the rim.

2. A stocking form comprising an apertured web having longitudinal and transverse reinforcing ribs, a rim about the web and edges outside the rim, the thickness of the form being greater at the rim than the thickness of the body of the web. 45

3. A stocking form comprising an apertured web having longitudinal and transverse reinforcing ribs, flanges on opposite sides of the form about the web and edges outside the flanges, the thickness of the form being greater at the flanges than at the web and the contour being relieved between the flanges and the edges of the form. 50

4. A stocking form having an apertured web bounded by flanges of greater thickness than the web on both sides of the form adjacent each edge, and having an edge outside the flanges. 55

5. A stocking form having a web bounded by flanges of greater thickness than the web on both sides of the form adjacent each edge, and having an edge outside the flanges, the web and the space between the flanges and the edges being apertured. 60

6. A stocking form having a thin perforated web corrugated to form ribs extending longitudinally of the form and flanges, thicker than the thickness given by the corrugations of the web about the edges of the form 70 extending transversely in both directions from the main plane of the web.

7. A stocking form having an interior perforated web ribbed longitudinally and transversely, a flange about each edge of the web 75 and an edge outside of each flange, the contour between the flange and edge being concaved to space the stocking from it.

FREDERICK C. SCHOLLER.
